UNITED STATES PATENT OFFICE.

EDWARD H. PARKS, OF PROVIDENCE, RHODE ISLAND, ASSIGNOR TO THE BROWN & SHARPE MANUFACTURING COMPANY, OF SAME PLACE.

BORING-MACHINE.

SPECIFICATION forming part of Letters Patent No. 323,723, dated August 4, 1885.

Application filed June 26, 1885. (No model.)

To all whom it may concern:

Be it known that I, EDWARD H. PARKS, a citizen of the United States, and a resident of the city and county of Providence, and State 5 of Rhode Island, have invented an Improvement in Chucking-Machines, of which the following description, in connection with the accompanying drawings, is a specification, like letters on the drawings representing like parts.

10 This invention relates to chucking-machines of that class employing a revolving table to receive the work to be operated on, while the head of the machine is provided with a reciprocating slide carrying a turret to contain 15 tools of various kinds, the said turret being adapted to be rotated on the slide, and to be locked thereto, to enable different tools to be presented to the work secured upon the revolving table.

20 Heretofore in such machines, so far as my knowledge extends, the table has been rotated in a vertical plane on a horizontal axis, while the turret-carrying slide has reciprocated in a horizontal plane. This has made it difficult 25 to secure the device or thing to be operated on—such, for instance, as a fly-wheel—upon the table, and when secured the strain incident to the weight of the device was exerted upon the holding means employed to retain 30 said work on the table.

The object of my invention is to provide a chucking-machine of the class designated, with a table adapted to rotate in a horizontal plane on a vertical axis, said table having a central 35 bore or opening to obtain constant clearance for chips, and in connection with said table to provide the head of the machine with a vertically-reciprocating slide carrying a turret, as well as to provide means for balancing the 40 reciprocating slide in the head. A further object is to provide the central bore of the horizontal table with a screw-threaded sleeve, and with means to raise or lower said sleeve with relation to the table, to afford a rest or 45 support at its center for such pieces of machinery or other devices which, on being placed upon the table, would not, by reason of their form or configuration, rest on the table at or about its center, as in the case of a 50 fly or band wheel, wherein the hub to be bored is of less length than the width of the rim,

which would thereby necessarily find support on the table at its rim only were it not for my invention. Further, as is well known, in machines of the class mentioned the reciprocating slide is provided with a locking-pin which enters a socket in the turret to lock or hold said turret in required position for the correct presentation of one of its tools to the device to be drilled or otherwise operated on, while 55 the head of the machine has a stationary tripping-dog which, during the upward movement of the slide, operates a spring-actuated lever pivoted to said slide, said lever thereupon withdrawing the locking-pin connected 60 therewith from its socket in the turret to release the latter and permit its rotation on the slide. By reason of the tripping-dog being stationary or firmly fixed to the head, it has heretofore been necessary to move the slide 65 its full stroke in the head in order to disengage the locking mechanism and release the turret to permit the latter to be partially turned on its axis and enable a second tool 70 to be presented to the work placed on the 75 table.

One of the objects of the present invention is to provide an adjustable or movable tripping-dog, and means for adjusting said dog in the head, so that, when desired, and upon adjustment of the dog, it is only necessary to move the slide a partial stroke to cause the locking-pin to be withdrawn from the turret 80 to release the same.

A still further object of my invention is to 85 provide a tool-guide adapted to be adjusted in the head of the machine and to be clamped thereto, the said tool-guide embracing or engaging a tool to retain it in proper position as against spring or vibration thereof while 90 being used in drilling or boring. This is more essential in relation to tools of some length, and when the cored hole in the hub of the fly-wheel, for instance, is not concentric with its rim, thereby necessitating a greater amount 95 of metal to be bored or drilled out at one side of said cored hole than the other, the tool in such case having a tendency to follow the cored hole, and thus depart from its proper position.

The object of the tool-guide is to prevent all 100 such spring or divergence of the tool from its correct position.

The invention is more fully set forth in the following description and claims.

Referring to the drawings, Figure 1 is a side elevation, partly in vertical section, of a machine embodying my invention; Fig. 2, a detail to be referred to; Fig. 3, an enlarged detail in elevation and section of part of the table and head, showing as well the slide-turret and tool-guide. Figs. 4 and 5 are details of parts of the tool-guide; Fig. 6, a vertical section of part of the head, to show certain details of construction; Fig. 7, a front elevation of the head with the slide removed; Fig. 8, a partial sectional view of the head, to show the turret-locking pin and lever and the adjustable tripping-dog; Fig. 9, a detail to be referred to, and Fig. 10 a plan view of the machine.

The base A has an attached column or standard, B, having head B', and is provided with a bearing, a, to receive the hollow spindle c of the table C, revolving in a horizontal plane, the loose friction-collars c' being interposed between the upper end of the bearing a of the base and the under side of the revolving table C, to distribute friction, as is well understood. The under side of the table C is provided with a bevel-gear, c'', to engage with a bevel-pinion, c', fixed on the driving-shaft 2, having bearings in the base A, and receiving the cone-pulley 3, to enable the shaft to be driven. The revolving table is provided at its center or bore with a sleeve, c'', which is screw-threaded on its outer surface and engages with a geared and threaded nut, d', said geared nut meshing with teeth cut on the inner end of a shaft, d'', which at its outer end extends through the bearing d' to the rim of the table, where it is adapted to receive a socket-wrench. (Not shown.) By this means the shaft may be rotated to move the nut d', and thus in turn raise or lower the sleeve c''.

In Fig. 3 the sleeve is shown in partly raised position to bring the bushing 7 (inserted in the bore of the sleeve) against the under side of the hub 4 of the band or fly wheel 5, which is placed on the table, thereby giving support to said hub when operated upon by the tool, and which also enables the feed of the tool to be increased to obtain more speedy results. The slide E has a reciprocating movement in a vertical plane and is provided with a turret, F, of ordinary construction, the said slide being balanced in the head by means of the weight f, having chains f' running over the rolls f'' f''', respectively secured to the standard B and head B', the said chains being attached to the slide at f', as shown in Fig. 6. The balancing-weight f enables an operator to more easily adjust the slide in the head. The lever g pivoted to the slide E receives a pin, g', which projects through the said slide (see Fig. 8) and enters a socket in the turret in the usual manner to lock or hold the turret to said slide as against rotation, the lever being engaged by a spring, h, the tendency of which is to force the pin forward into the

turret. A groove, g', is made in the head B, as shown in Fig. 8, which receives a rack-bar, g'', having a projection, g'', at the upper end, 70 through one side of the head and receiving a tripping-dog in lieu of the common or well-known stationary tripping-dog heretofore employed. The rack-bar is engaged by a pinion, g'', on the inner end of the shaft g'', extending 75 through one side of the head and receiving a knurled head, g'', keyed thereto and inclosing a spring, g'', which constantly forces the knurled head against the outer toothed surface of the bushing i' firmly secured in the head B'. The inner end of the knurled head is also provided with teeth or serrations to engage the teeth of the bushing i, and thus serve as a clutch or locking device to retain the pinion g'' and rack g'' in adjusted position. 85

When it is desired to raise or lower the tripping-dog, the head g'' is drawn outward as against the action of the coiled spring g'', to disengage its teeth from the toothed bushing, when said head is turned to operate the pinion g'', and thus in turn to raise or lower the tripping-dog to any desired position. By such adjustment it will be noticed that the upper end of the lever g pivoted to the slide will sooner or later strike the projection g'' of 90 the tripping-dog and cause the withdrawal of the pin g'' from the turret F, whereby the said turret may be turned to permit different tools to be presented to the device operated on without causing the slide to be moved its entire stroke. The tripping-dog is shown in front elevation, Fig. 7, wherein the slide is removed. When the slide is in its proper position in the head, it bears against the flange h' on the side of the tripping-dog, to retain it 95 in the groove h as against being forced forward by the action of the pinion during adjustment. The tool-guide K is attached to the stem k, which is held in the head B' by the clamp k', having adjusting-screw k'' to enable the tool-guide to be raised or lowered and retained in adjusted position. The rear end of the tool-guide moves in the groove k'', planed in the face of the standard A, while the forward end of the said tool-guide 100 has in the present instance two plates, k'', bolted thereto and adapted to enter the grooves k''' cut in the tool k'', on opposite sides thereof, the said plates firmly holding the tool as against spring or vibration in any direction, while at the same time permitting said tool to be raised or lowered. 110

The mechanism for operating the slide which carries the turret is of usual construction, and consists, briefly, of the upright shaft 125 m, having hand-wheel m', bevel-pinion m'', meshing with bevel-gear m''' on shaft m'', having bearings in the head of the machine and provided with the gears m'', which mesh into the racks m'', (see Fig. 6,) secured to the back 130 of the slide E, so as to enable the slide to be operated by hand. The slide is automatically operated by means of the band passing about the pulley n on shaft 2, (see Fig. 1,) and disk

n' on shaft *n²*, having bearings in the arm *n³*, and provided with spring *n⁹* and adjusting-nut *n¹⁰*. (See Fig. 2.) The disk *n'* is engaged by the friction-roll *n⁴*, on cross-shaft *n⁵*, (see Fig. 10,) secured in bearings *n⁶* attached to the standard B. This shaft *n⁵* has a bevel-gear, *n⁷*, engaging the bevel-gear *n⁸* on rear end of the worm-shaft *o*, which at said end has bearings in the yoke *o'* retained on the shaft *n⁵*, as shown in Fig. 10. The worm-shaft *o* extends toward the forward part of the head B' and receives the worm *o²*, (see Fig. 7 and dotted lines, Fig. 6,) which meshes with the worm-gear *o³*, fast on the shaft *m⁴*, as clearly shown in Fig. 7. The forward end of the worm-shaft *o* is supported by the yoke *p*, having a stem, *p'*, adapted to be moved vertically in the bracket *p²*. An arm, *p³*, (see Fig. 7 and dotted lines, Fig. 6,) enters a slot in the stem *p'*, and is fast on the shaft *p⁴*, having bearings in the head B' back of the slide, said shaft at the opposite side of the head B' receiving a crank-lever, *r*, (see Fig. 1,) which is engaged by the spring-actuated catch *s*. This catch holds the lever *r* and connected mechanism in adjusted position to keep the worm in engagement with the worm-gear. Upon withdrawal of the spring-actuated catch *s* the crank-lever is released and the worm falls away from the worm-gear by gravity, thus preventing further automatic feed of the slide.

The catch may be operated by hand through the aid of the thumb-piece *s'*, (see Fig. 9,) or automatically by means of the spring-actuated pin *s²*, having a wedge-shaped inner end to enter a mortise in the stem of the spring-catch, the said pin *s²* being forced back into the head as against the action of the spring *s'*, to cause the retraction of the spring-catch by means of the nut *t*, adjustably secured in the slot *t'* in the side of the slide E, as clearly indicated in Fig. 1.

The nut may be so adjusted as to disconnect the slide from its automatic feed at any given point in its downward movement, as is well understood.

I claim—

1. In a chucking-machine, the bed provided with a horizontal table having a central bore,

and adapted to be rotated as specified, combined with a head having a vertically-reciprocating slide provided with a turret, substantially as set forth.

2. In a chucking-machine, the bed provided with a horizontal table having a central bore and adapted to be rotated, as specified, combined with a head having a vertically-reciprocating slide provided with a turret and a balance-weight, substantially as set forth.

3. The horizontal table provided with a central bore and screw-threaded sleeve, a geared nut, and means to operate said nut to raise or lower the sleeve, substantially as set forth.

4. The combination, with the head having a reciprocating slide provided with a turret, and with a pivoted lever having a locking-pin to engage the turret, as specified, of a tripping-dog having a toothed extension or rack, and means for raising or lowering said tripping-dog in the head, for the purpose specified.

5. The head provided with a reciprocating slide having a turret, and a pivoted lever having a pin to engage the turret, combined with a tripping-dog having a rack and adapted to slide in the head, the pinion *g⁵* and its shaft, and means for locking the shaft in required position, as set forth.

6. The head provided with a clamp, as specified, and the tool-turret, combined with the tool-guide, having a stem to enter the clamp, and provided with jaws to engage a tool of the turret, in the manner and for the purpose described.

7. The head provided with the clamp and the turret, having tools with grooves therein, as specified, and the standard having the groove *k³*, combined with the tool-guide provided with the stem, the jaws, and the rearward extension, substantially as and for the purpose set forth.

In testimony whereof I have signed my name to this specification in the presence of two subscribing witnesses.

EDWARD H. PARKS.
